UNITED STATES PATENT OFFICE.

STEPHEN C. PORTER, OF NEW YORK, N. Y., ASSIGNOR TO THE PORT-O-PHONE CORPORATION, OF ESOPUS, NEW YORK, A CORPORATION OF NEW YORK.

TELEPHONE APPARATUS.

1,246,317.

Specification of Letters Patent. Patented Nov. 13, 1917.

Application filed October 4, 1916. Serial No. 123,608.

To all whom it may concern:

Be it known that I, STEPHEN C. PORTER, a citizen of the United States, residing in the borough of Manhattan, city of New York, county of New York, and State of New York, have invented new and useful Improvements in a Telephone Apparatus, of which the following is a specification.

This invention relates to telephone apparatus and more particularly to the receiving portion thereof, and has for its object to make it possible to use the receiver either at the ear, in the ordinary manner, or while stationarily supported in conjunction with an amplifier. In the latter event the user does not have to pick up the receiver at all and the incoming message may be audible to others in the room, whereas if the conversation is to be private the other mode of use may be followed. These objects are attained by the combination of a receiver and a holder wherein the same may be placed in communication with an amplifier, which latter is preferably embodied with the holder in a form of low stand adapted to rest upon the desk or table.

In the accompanying drawings:

Figure 1 is a perspective view of the apparatus, with the receiver out of its cup;

Fig. 2 is a vertical longitudinal section through the stand and amplifier with the receiver in place and partly in section and partly in elevation; and

Fig. 3 is a rear elevation of the stand and amplifier.

The receiver 1 is preferably of substantially flat circular form, 2 being its sound outlet and 3 the diaphragm, and the remainder of its internal structure being immaterial as far as the invention is concerned.

The other part of the combination com-

prises an amplifier 4, here shown in the form of a straight horn, and a holder 6, in which the receiver may be placed with its sound exit in communication with the small end of the amplifier. Such holder preferably consists of an open shallow horizontal cup secured upon the upturned small end 5 of the horn. This end passes through the bottom 45 of the cup, to form a projecting rim 8, which meets the face of the receiver around the sound exit, in order to prevent the escape of sound waves from between the receiver and the amplifier when the receiver is in 50 place. A foot 7 united to the small end of the horn or to the cup, or to both, steadies the amplifier and cup in their substantially horizontal positions. The axis of the amplifying horn, it may be noted, is preferably 55 inclined somewhat upward.

While the foregoing is a preferred and simple embodiment of the invention, it will be understood that numerous changes may be made, as for example in respect to the 60 nature and form of the amplifier and receiver holder and their mode of support, without departing from essentials.

What I claim as new is:

A device for use in connection with a 65 telephone receiver comprising a substantially horizontal horn having its small end upturned, a cup upon said upturned end, and a foot at said end projecting below the bend and laterally for supporting and 70 steadying the horn and cup at the rear, the device being supported forwardly of the foot by the horn itself resting upon the underlying surface.

Dated, September 25th, 1916.

STEPHEN C. PORTER.
